UNITED STATES PATENT OFFICE.

CHARLES WAINWRIGHT AND FRED J. CARNEY, OF ERIE, PENNSYLVANIA.

GOVERNING DEVICE FOR FLUID-COMPRESSORS.

1,061,208.

Specification of Letters Patent.

Patented May 6, 1913.

Application filed May 29, 1912. Serial No. 700,444.

To all whom it may concern:

Be it known that we, CHARLES WAINWRIGHT and FRED J. CARNEY, citizens of the United States, residing at Erie, in the county 5 of Erie and State of Pennsylvania, have invented new and useful Improvements in Governing Devices for Fluid-Compressors, of which the following is a specification.

The general object of the invention is to 10 adapt a turnable or Corliss intake valve to operate as an unloader for the cylinder of a fluid compressor. And to this end the invention consists in a valve consisting of two parts, each having a series of ports arranged 15 in echelon with respect to the ports of the other part and means arranged to be operated with a predetermined pressure in the receiver of the compressor to effect the moving of one of the valve parts into such 20 position as will place the ports of the said valve part in alinement with the ports of the other valve part.

Other objects will appear and be better understood from that embodiment of my 25 invention of which the following is a specification, reference being had to the accompanying drawings forming part hereof, in which—

Figure 1 is a detail vertical longitudinal 30 section of the cylinder of a double acting air compressor constructed to coöperate with my improved valve. Fig. 2 is a vertical cross sectional detail of the cylinder shown in Fig. 1 showing the valve partly in section and in elevation and assembled with the cylinder. Fig. 3 is a detail longitudinal section of the inner part of the valve. Fig. 4 is a vertical cross section of Fig. 3. Fig. 5 is an end elevation of Fig. 3. Fig. 6 is a 35 view similar to Fig. 3 of the outer part of the valve. Fig. 7 is a vertical cross section of Fig. 6. Fig. 8 is an end elevation of Fig. 6. Fig. 9 is a diagrammatic view of the parts arranged in unloading position and at 40 the beginning of turning movement in the direction of the arrow. Fig. 10 is a view similar to Fig. 9 but showing the position of the parts when approximately one-half the turn of the valve has been completed.

The cylinder *a* is constructed with the usual bore *b* for the piston, (not shown), the chamber *c* which communicates with the source of supply through an opening *d*, the outlet ports *e*—*e* which communicate with the chamber *f* and a port *g* which establishes communication between the chamber *f* and a

suitable connection which conveys the compressed fluid. The outlet valves which control the ports *e*—*e* may be of any suitable construction and are not herein shown. The cylinder herein shown is of the double acting type and is formed with inlet ports *h*—*h*. It is to be understood that this showing is merely conventional and that the principle of my invention which is for unloading the cylinder when a predetermined pressure is attained in the receiver of the compressor, may be carried out with a cylinder of the single acting type or one having a single intake *h* and a single outlet *e*.

In a double acting cylinder of the type shown the action of the piston causes practically a continuous suction through the opening *d* and an alternate suction through the ports *h*—*h*. The air drawn through the ports *h*—*h* passes into the valve chambers *i*—*i* which also form part of the intake of the compressor, and thence into the chambers *k*—*k* also forming part of the intake and finally into the cylinder *a* where it is compressed and discharged through the outlets *e*.

The passages through the chambers *i*—*i* are controlled by the valves, one of which is shown assembled in Fig. 2 and indicated generally by *l*. The outer part of cage of each valve as shown in Fig. 6 and indicated by *5*, is a hollow cylindrical structure of such size as to nicely fit in the chamber *i*. The inner part of each valve as shown in Fig. 3 and indicated by *6* is a hollow cylindrical structure of such size as to nicely fit within the cage *5*. The valve is retained in the chamber by caps or bonnets *7* and *8* which are suitably fastened to the cylinder so as to form closures for the ends of the chamber *i* and are formed with bosses *9*—*9* to bear on the opposite ends of the valve but not sufficiently tight to prevent the turning thereof. The cap or bonnet *8* is formed with a bearing *10* for the stem or shaft *11* which has at its inner end a rib *12* arranged in a slot *13* at one end of the cage *5*. The outer end of the stem *11* connects with a crank *13* which is rocked by a suitable connection in the form of a rod (not shown) carried by the eccentric or other suitable part of the pump mechanism of the compressor. The bonnet *7* is formed with a bearing *14* for a stem *15* carried by the members *6*, and a cap *16* connected to the outer end of the bearing *14* is adapted for

- receiving a rod 17 connected at one end with the stem 15 and having its outer end surrounded by a spring 17 which is adjusted by a nut 18. A pin 19 carried by one of the parts of the valve such as the part 6, fits into a groove 20 in the other part of the valve and thereby prevents the independent turning of the said parts but admits of sliding or longitudinal movement of the inner part 6.
- 10 The outer end of the part 6 is held by the spring 17 in contact with the bonnet or cap 7 and when so positioned the stem 15 is spaced from the cap 16 and the intervening space forming a chamber 21 which has a port 22 into which is directed a pipe 23 connected with the controller (not shown) which controller is also connected to any suitable point in the receiver of the compressor.
- 15 The cage 5 has oppositely disposed elongated ports 24-24 which correspond to similarly disposed ports 25-25 in the member 6, these ports are always in alinement, being so held through the interlocking effect afforded by the groove 20 and pin 19. The portions 26-26 and 27-27 of the walls of the parts 5 and 6 between the openings 24-24 and 25-25 are of such widths as to blank the port *h* and chamber *k* when the openings 24 and 25 are turned out of alinement with such port and chamber. Adjacent to diagonally opposite sides of the openings 24-24, there are formed a double series of ports 28-28 and similarly disposed with respect to the openings 25-25 in the part 6 are a double series of ports 29-29. The ports 29 are so disposed with respect to the ports 28 of the part 5 that when the part 6 is held by the spring in the position shown in Fig. 2, the said ports 29 will be arranged in echelon with respect to the ports 28 so that passage for the fluid through the parts of the valve cannot be had through these ports. When, however, a sufficient pressure is attained in the receiver of the compressor to overcome the resistance offered by the controller (not shown) the compressed fluid enters the pipe 23 and passes into the chamber 21 where, by pressing on the stem 15, it effects the longitudinal movement of the part 6 against the action of the spring 17. Now as the part 6 moves longitudinally, the ports 29 thereof are brought into alinement with the ports 28 as shown in Figs. 9 and 10, and since the arc of turning movement of the valve *l* is equal or approximately so to the angular distance between remote sides as indicated by 31-31 of either of the openings 25 and either series of ports 29 and further since the blank portions 32-32 and 33-33 between the openings and ports of the parts 5 and 6 respectively are less in width than the intake and the chamber *k* it will be manifest that when the ports are in alinement as shown

in Figs. 9 and 10 and the valve turned by the mechanism as previously stated, the intermittent communication between the cylinder and its source of fluid supply which takes place when the ports are in echelon will be destroyed and continuous communication effected instead. 70

Bearing in mind that when the parts are arranged as shown in Fig. 2 and the valve turned so as to establish communication between the interior of the cylinder and the chamber *c* the piston will be on its suction stroke. When at the end of such stroke the valve will be turned so as to cut off communication with the chamber *c* so that when the piston returns, the entrapped air will be compressed and forced through one of the valves into the chamber *f*. But when the receiver pressure has operated the valve parts so as to place the ports of one part in alinement with those of the other then instead of the valve cutting off communication with the chamber *c* at the end of the suction stroke of the piston the several series of ports will be so arranged as to establish communication between the interior of the cylinder and the chamber *c* throughout the compression stroke of the piston so that the air drawn into the cylinder on the suction stroke will now be forced outwardly 95 and against no other resistance than that offered by the atmosphere which for present purposes may be taken as nothing. This of course will have the effect of completely unloading the cylinder or in other words, relieving the piston of doing further work until such time as the container pressure is reduced to a point where the controller (not shown) may effect the cutting off of the fluid supply to the chamber 21 whereupon 100 the parts of the valve will be restored to their normal positions by the spring 17 and the valve permitted to operate again as the ordinary intake valve. 105

What is claimed as new is:

1. In a governing device for fluid compressors the combination with the pump mechanism; of mechanically operated means arranged to operate intermittently on the intake of the compressor and means arranged to be operated with a predetermined pressure in the receiver of the compressor to co-act with the first mentioned means for the purpose set forth. 110
2. In a governing device for fluid compressors the combination with the pump mechanism; of mechanically operated turnable means arranged to operate intermittently on the intake of the pump mechanism and means arranged to be operated with a predetermined pressure in the receiver of the compressor and to co-act with the first mentioned means for the purpose set forth. 120
3. In a governing device for fluid compressors, the combination with the pump 130

mechanism; of a mechanically turnable hollow cylindrical intake valve including a slideable ported element arranged to be operated with a predetermined pressure in the receiver of the compressor for the purpose set forth.

4. A combined intake valve and controlling device for fluid compressors comprising, interfitting mechanically operated turnable members each of which has ports normally out of alinement with the ports of the other member, one of said members being ar-

ranged to be moved with a predetermined pressure in the receiver of the compressor to effect the alining of its ports with those of the other member for the purpose set forth.

In testimony whereof we have affixed our signatures in presence of two witnesses.

CHARLES WAINWRIGHT.
FRED J. CARNEY.
